GRINDING DEVICE

George J. Batzer, Cleveland, Ohio, assignor to
Micromatic Home Corporation, a corporation
of Michigan

Application September 15, 1930, Serial No. 481,893

3 Claims. (Cl. 51—184.3)

This invention relates to improvements in cylinder hones or lapping tools of the type commonly employed for finishing the bores of engine cylinders or other objects, and has for an object to provide means whereby such bores may be accurately honed or finished.

Another object is to provide a tool of the type described of new and novel construction.

Another object is to provide a tool of the type described in which means are provided for eliminating any inaccuracy in the work produced due to misalignment of the driving means with the axis of the bore being worked upon.

Another object is to provide a tool of the type described in which the axis of the driving member and the axis of the body member may be eccentric to each other during a grinding or lapping operation.

Another object is to provide a tool of the type described in which the axes of the driving member and of the body member may be disposed at an angle with respect to each other without affecting the proper operation of the tool.

Another object is to provide a tool of the type described in which the axes of the driving member and of the body member may be either eccentric to each other or angularly disposed with respect to each other without affecting the proper operations of the tool.

Further objects will be apparent in the following specification, reference being had to the accompanying drawings, in which like numerals refer to like parts throughout the several different views.

In the drawings:

Fig. 1 is a partially sectional view taken axially through my improved hone.

Fig. 2 is a side elevation of the hone shown in Fig. 1, but viewed in a direction ninety degrees removed therefrom relative to its axis.

Fig. 3 is a fragmentary side elevation of the upper end of the hone shown in Figs. 1 and 2, taken in the same direction as in Fig. 1 and 90 degrees removed from the view shown in Fig. 2.

Fig. 4 is a sectional view taken on the line 4—4 of Fig. 1, illustrating the construction of one of the joint members through which the drive is taken.

Fig. 5 is a sectional view taken on the line 5—5 of Fig. 1, illustrating the construction through another one of the joint members through which the drive is taken.

Fig. 6 is a fragmentary sectional view taken axially through the central portion of a device shown in the previous figures and illustrating

the universal joints in the controlling means for the expanding cones.

Fig. 7 is a sectional view taken on the line 7—7 of Fig. 1.

Fig. 8 is a sectional view taken on the line 8—8 of Fig. 1.

Fig. 9 is a sectional view taken on the line 9—9 of Fig. 1.

Fig. 10 is a sectional view taken on the line 10—10 of Fig. 1.

Fig. 11 is a plan view of one of the abrasive members.

Fig. 12 is a side elevation of one of the abrasive members.

The main features of the construction of the hone shown in the accompanying drawings are similar in construction and operation with the hone disclosed in Letters Patent of the United States issued September 22, 1925, to Theodore Restel, and numbered 1,554,760. The inventive features of the present device over that of the Restel construction, consist mainly in the introduction of joints affording desired movement between the driving member and the body of the hone, but also includes certain other features tending towards economy in manufacture and greater satisfaction in operation.

Referring first to the body end of the hone, it will be noted that it comprises a body portion 20 of octagonal section as best illustrated in Figs. 8, 9 and 10. The upper end of the body portion 20 is provided with an integral circular, externally threaded, extending portion 21. The body 20 and portion 21 are provided with an internal bore 22 of constant diameter from the upper end of the portion 22 to adjacent the bottom of the body 20, the portion not bored out forming a stop wall 23 which will be referred to later. The body portion 20 is radially slotted as at 24 in four different places, each ninety degrees removed from the adjacent one, these slots being disposed centrally of the corresponding exterior face of the body 20 and extend completely through the body 20 into the bore 22 for the full length of the body portion 20.

Secured to the exterior faces of the body member 20, between each of those faces which are slotted as at 24, by means of screws 25, or other suitable means, is a member 26. These members 26 extend substantially the full length of the body member 20 and adjacent sides of adjacent members 26 cooperate with each other to form between them a groove 27 of a width equal to the width of the octagonal face of the body member 20 disposed between them. The outer faces

of the members 26 are equally disposed at all points on their surfaces from the center of the body member 20 to thus effect a generally cylindrical exterior contour to the body portion of the hone. Although I have shown these members 26 as formed separately from the body members and secured thereto by means of screws such as 25, it will be apparent that in the broader aspects of my invention the portions 26 may be formed integral with the body portion 20, but I desire to form them separately for the sake of economy in manufacture.

Radially slidably received within each of the grooves 27 is an abrasive or stone carrier 28 provided with an abrasive member or stone 29 set into its exterior face for substantially the entire length thereof. Each carrier 28 has integrally formed thereon at one end a lug 30 and adjacent the other end another lug 31, the lug 30 being provided with an inclined face 32 at its inner edge and the lug 31 being provided with a similar, and similarly disposed, angular face 33. The lugs 30 and 31 are of a width suitable for their radially slidable reception in the grooves 24, and are of sufficient depth to permit them to project into the bore 22.

Axially slidably received in the bore 22 of the body 20 and extension 21 are a pair of members 35 and 36 having similarly disposed cone surfaces 37 and 38 respectively. The members 35 and 36 are rigidly connected together by a connecting portion 39 so as to insure equal movement of both members in the bore 22. The members 35 and 36 are spaced from each other a distance corresponding to the spacing of the lugs 30 and 31 and their cone surfaces 37 and 38 are adapted to engage the beveled surfaces 33 and 32 respectively of the lugs on the various stone carriers 28. It will thus be apparent that when the elements are positioned as indicated in Fig. 1 and the cone element assembly is moved downwardly, or in the direction of the apexes of the cones, that engagement of the surfaces 37 and 38 with the beveled surfaces 33 and 32 on the lugs will force the stone carriers radially outwardly with respect to the body of the hone, and thereby increase the effective diameter of the grinding surface of the body.

The upper and outer corner of each lug 30 is also beveled as at 43, best shown in Figs. 1 and 12. Surrounding the upper end of the main body portion 20 and slidably axially thereof is a ring 44 provided with a beveled face 45 complementary in angularity to the angularity of the beveled portions 43 of the lugs 30, and adapted to contact therewith. The ring 44 is resiliently urged into constant contact with the beveled surfaces 43 of the lugs 30 in the following manner. A ring 46 is externally threaded on extension 21 immediately above the ring 44. The ring 46 is provided with a plurality of blind apertures 47 opening onto the lower face thereof in alignment with the ring 44, and in each of these apertures 47 is positioned a spring pressed plunger 48, the projecting ends of which bear against the ring 44 and constantly urge it against the bevel faces 45 and the lugs 30. The ring 44, under the pressure of the pins 48, therefore tends to hold the stone carriers in retracted position against the cone surfaces 37 and 38, and when the cone surfaces are moved upwardly, acts to force the stone carriers to recede radially inwardly a corresponding amount.

Extending upwardly from the upper cone member 36 is a hollow extension 50 provided between

its ends with an axially elongated slot 51 passing diametrically through it. Through this slot a pin 52 extends and further projects outwardly through the axially elongated slots 80 which are diametrically disposed in the extensions 21. Held under compression between the pin 52 and the bottom of the bore of the extension 50 is a coil spring 53. It will be apparent that when the pin 52 is in contact with the upper end of the slot 51 the spring 53 is confined between two fixed portions of the same member, and consequently can exert no pressure which would influence a change in the position of the member. However, in order to utilize the spring 53 as means for moving the cones 37 and 38 towards expanded position, a ring or collar 54 is threaded on the extension 21 and is adapted to bear against the ends of the pin 52 which project beyond the peripheral surface of the extension 21 as indicated best in Fig. 6. Thus by threading down the collar 54, the pin 52 may be moved downwardly in the slot 51 and the compressive force of the spring 53 thereby employed to urge the cone members 35 and 36 downwardly. The collar 54 is provided with a downwardly extending skirt portion 55 which encloses the ends of the pin 52 in order to maintain it against inadvertent displacement, as best shown in Fig. 6.

The operation thus far described will be apparent and, briefly, is as follows. Considering the parts to be in the position indicated in Fig. 1, it will be noted that if the collar 54 is threaded downwardly on the extension 21 the pin 52 will be urged downwardly in the slot 51, and if sufficient resistance is offered to expansion of the abrasive elements 29, the pin 52 will move down in the slot 51 and the compressive force of the spring 53 will be exerted to move the cones downwardly. As the resistance to expansion of the abrasive elements 29 is relieved, as by removing metal of a bore being worked upon, the cone assembly will, in moving downwardly, eventually bring the pin 52 again into contact with the upper end of the slot 51, at which time no further expansion of the abrasive elements 29 may occur, and thus the ultimate effective size of the bore to be ground may be accurately predetermined by proper positioning of the collar 54. The lower closed end 23 of the body member 20 will act as a positive stop to limit the maximum downward movement of the cone assembly, it being provided with a recess 56 complementary to the lower end of the cone 37 and is apertured as at 57 to provide a knock-out opening.

In operating a tool of the type described it will be apparent that means must be provided for both rotating and reciprocating the tool, and means must be provided permitting a retraction of the cone in order to permit the body portion of the hone to be collapsed as an aid to its insertion in or withdrawal from the bore being worked upon. The means for accomplishing this is as follows.

On the upper end of extension 21 is threaded a member 60 the upper end of which is provided with a diametrically extending upwardly projecting tongue 61, best shown in Figs. 5 and 6. Resting upon the upper surface of the member 60 is a member 62 provided with a diametrically disposed slot 63, best shown in Fig. 6, complementary to the tongue 61 and receiving the latter therein. This thus forms a driving connection between the members 60 and 62 for transmitting rotational movement between them. Disposed over the member 62 is a member 64 and the mem-

bers 62 and 64 are provided in their adjacent faces with complementary diametrically disposed semicylindrical grooves 65, in each end of which is received a metal ball 66 which maintains the members 62 and 64 in slightly spaced relationship. These balls 66 thus provide, in conjunction with the grooves 65, a driving engagement between the members 62 and 64 for transmitting rotational movement between them. In holding the members 62 and 64 in slightly spaced relationship, the member 64 is permitted a slight pivotal movement relative to the member 62 about a line connecting the centers of the balls 66 and, further, due to the connection between them the member 64 may move bodily relative to the member 62 in the direction of the grooves 65.

Received over the member 64 is a member 68 and the adjacent faces of the members 64 and 68 are provided with diametrically disposed semi-cylindrical slots 69 similar to the slots 65, but 90 degrees removed therefrom relative to the axes of these members. Balls 70 are received in the opposite ends of the cooperating grooves 69 to effect a driving engagement between the members 64 and 68 as well as to permit a slight pivotal movement of the member 68 relative to the member 64 about a line connecting the centers of the balls 70. As will also be apparent the members 64 and 68 are thus capable of bodily movement relative to each other in the direction of the grooves 69, and this movement combined with the similar relative movement between the members 62 and 64 effects a construction equivalent to that obtained in an Oldham coupling, permitting a driving effort to be applied through these members although the axes of the members 62 and 68 may be eccentric to each other. The member 68 is further capable of a limited amount of universal movement relative to the member 62 for a purpose which is self-evident but will hereafter be more fully described.

The member 68 is provided with a tubular upward extension 73 which is threaded internally into the bore of a partially tubular driving member 74, the upper end of which may be provided with a tang 75 of a conventional construction permitting its engagement with the spindle of a drill press or other machine tool. A sleeve member 76 encircles the members 62, 64 and 68 and threadably engages the member 68 at its lower end. The upper end of the sleeve 76 is turned as at 77 so as to overlap the upper face of the member 68, but terminates in freely spaced relation with respect to the extension 73, and a roll of ball bearings 78 is disposed between the flange 77 and the member 68, sufficient clearance being left between the sleeve 76 and the members within the same at all points so as not to materially interfere with the universal and limited eccentric movement of the member 68 relative to the member 62 as previously described. The sleeve 76 thus prevents substantial axial displacement of the members 62, 64 and 68 and of the balls 66 and 70 in order to maintain them in rotatable driving engagement, and at the same time prevents axial displacement of the member 68 relative to the member 60 so as to insure corresponding axial movement between the driving member 74 and the body of the hone.

As previously described and as best illustrated in Fig. 6, the extension 21 is provided at opposite sides and in diametrically opposed relationship with axially parallel slots 80 in which the ends of the pins 52 are received and guided in their movement relative to the extension 50 and the

cone assembly. A second pin 81 projecting diametrically through the extension 50, but fixed against relative axial movement therein, projects at each end into the grooves 80 in order to insure the extension 50 turning with the extension 21 at all times and to prevent any possible binding of the pin 52 in the slots 51 and 80. Projecting through the extension 50 above the pin 81 is a pin 82, the entire length of which is disposed within the periphery of the extension 50. Engaged over the pin 82 within the bore of the extension 50 is a spherical end 83 of a rod 84 which extends therefrom up into the bore 85 of the driving member 74. The opening 86 in the ball 83 is of larger diameter at its outer ends than at its center, as indicated in Fig 6, in order to permit a limited amount of universal movement of rod 84 with respect to the member 50, the amount being sufficient to permit the rod 84 to swivel to accommodate itself to any universal movement of the members in the driving connection between the driving member 74 and the extension 21. Sufficient clearance is also provided in the bores of the members through which the rod 84 extends so as not to restrict the possible eccentric movement between the driving member 74 and the body of the hone as provided for by the elements within the sleeve 76.

The upper end of the rod 84 is provided with an eye 88 in which is rotatably received the pin 89 which extends diametrically with respect to the driving member 74 and the ends of which project outwardly beyond the periphery of the driving member 74 through diametrically disposed axially parallel slots 90 in the driving member 74. Outside of the driving member 74 a member 91 having cam faces 92 and 93 is secured against relative rotation to each end of the pin 89, and each member 91 is provided with a manually operable handle portion 94. As best indicated in Fig 3, the cam face 92 is positioned at a less distance from the center of the pin 89 than the cam face 93. The driving member 74 adjacent the slot 90 is externally threaded as at 95 and threaded on the portion 95 is a ring member 96 against which the cam faces 92 and 93 are adapted to bear depending upon the pivotal position of the member 91.

It will be apparent from the foregoing that the pin 89 passing through the driving member 74 is maintained at a fixed distance with respect to the extension 50 of the cone assembly. If, therefore, the various elements of the hone are in the position illustrated in Fig. 1, with the pin 52 contacting against the upper end of the slot 51, and with the ring 96 threaded up into contact with the cam face 92 of the member 91, and the handles 94 then operated to bring the cam faces 93 into contact with the upper face of the ring 96, the pin 89 will be moved upwardly relative to the upper face of the ring 96 and, acting through the rod 84, will move the cone assembly upwardly in the bore of the extension 21 against the resistance of the spring 53, and will thus permit the effective diameter of the abrasive elements 29 to be decreased a corresponding amount. Likewise, it will be apparent that by suitable positioning the collar 96 on the driving member 74, it may be employed as an adjustable stop for determining the expansive movement of the cone assembly, as it may be so positioned that the cam surface 92 may be caused to bear against the collar 96 before the pin 52 reaches the upper end of the slot 51 during expansive movement of the device.

In operation, the tang 75 is suitably secured 75

within a machine tool, as for instance a drill press, and the article, not shown, whose bore is to be worked upon, is aligned as closely as is conveniently possible with the axis of the driving member 14. Should there be any slight misalignment, either the universal action or the eccentric action previously described between the driving member 14 and the body of the hone and between the rod 84 and the cone assembly 5 will permit the hone to adjust itself to the bore. The hone is then collapsed sufficiently to permit its insertion into the bore to be worked upon. This may necessitate not only threading the ring 54 upwardly on the extension 21 of the body member 20 so as to permit the proper vertical or retracting movement of the cone assembly, but may also include threading the ring 96 upwardly on the driving member 14 so as to permit the compression of the spring 53 regardless of the position of the cone assembly in 10 the bore of the body member. The hone being inserted in the bore is then rotated and caused to reciprocate, the collar 54 being threaded downwardly at intervals and the diameter of the bore being tested at intervals until the required bore is obtained. If, now, a number of other bores of the same diameter are to be machined, the handles 94 are positioned as indicated in 15 Fig. 3 and the collar or ring 96 threaded upwardly until it lightly but firmly engages the cam surfaces 92. The handles 94 are then rotated to bring the surfaces 93 into contact with the ring 96 and, as previously described, this causes an upward movement of the cone 20 assembly and corresponding compression of the spring 53, and permits the effective diameter of the abrasive elements 29 to be decreased under the collapsing action of the ring 44, or otherwise. The amount which the effective diameter of the hone is thus decreased will then 25 permit the hone to be inserted in the next bore to be machined, and the handles 94 may then be returned to the position indicated in Fig. 3, which thus frees the cone assembly from its restraint and leaves the spring 53 in condition 30 to again urge the cone assembly downwardly so as to cause the effective diameter of abrasive elements 29 to be increased. In this case, however, in view of the fact that the desired position of the collar 54, or of the collar 96, as 35 the case may be, which determines the effective diameter of the bore which will be machined, has already been predetermined for the particular size of the bore, and therefore as soon as the spring 53 has moved the cone assembly far 40 enough to bring the pin 52 into contact with the

upper ends of slot 51, or the cam face 92 into engagement with the collar 96, depending upon which is being employed as the limiting factor, it will be assured that the resulting diameter of the bore being worked upon is exactly the same as that previously provided, minus, of course, the small amount of wear which may have occurred in the abrasive elements 29 during the operation. This last amount of error will be relatively negligible in each case and may be corrected in each case by giving the collar 54 or the collar 96, as the case may be, a slight turn in a downward direction in passing from one bore to another in order to compensate for the wear of the stones 29.

10

15

Formal changes may be made in the specific embodiment of the invention described without departing from the spirit or substance of the broad invention, the scope of which is commensurate with the appended claims.

20

What I claim is:

1. In an abrading tool having an abrading head, provided with an abrading element radially adjustable therein; a drive element connected to said head for universal movement with respect thereto; an adjusting member located remotely from said head; a loading spring for urging said abrading element radially of said head; a universal joint; and means forming an operative connection between said abrading element and said member through said spring and said joint.

25

2. In an abrading tool having an abrading head, provided with an abrading element radially adjustable therein; a tubular drive element connected to said head for universal movement with respect thereto; an adjusting member located remotely from said head; a loading spring for urging said abrading element radially of said head and positioned within said drive element; a universal joint positioned within said drive element; and means in said drive element and forming an operative connection between said member and said abrading element through said spring and said joint.

40

3. In an abrading tool having an abrading element and a control element therefor, the combination in a universal joint for connecting said elements, of first and second pairs of balls, the control element having a groove to receive the balls of one pair and the abrading element being grooved to receive the other element, and additional grooved means connected between the balls of the respective pairs.

45

GEORGE J. BATZER.
